UNITED STATES PATENT OFFICE.

CHARLEY M. COX, OF BURR, KENTUCKY.

RAIL-JOINT.

1,158,789.

Specification of Letters Patent.

Patented Nov. 2, 1915.

Application filed August 17, 1914. Serial No. 857,147.

To all whom it may concern:

Be it known that I, CHARLEY M. Cox, a citizen of the United States, residing at Burr, in the county of Rockcastle, State of Kentucky, have invented certain new and useful Improvements in Rail-Joints; and I do hereby declare the following to be a full, clear, and exact description of the invention, such as will enable others skilled in the art to which it appertains to make and use the same.

This invention relates to a rail joint.

An object of the invention is to provide a joint for securing together the two adjacent ends of rail sections.

A further object of the invention is to provide a device of this character which will secure the ends of the rails together and yet will allow the same to expand or contract as affected by the heat or cold respectively.

A still further object of the invention is to provide such a device that the rails will be prevented from all relative vertical movement.

With these and other objects in view, such as will appear as the description progresses, my invention comprises the combination and arrangement of parts to be hereinafter more fully described, claimed and illustrated in the accompanying drawing, in which:

Referring to the drawing: Figure 1 is a perspective view of my device. Fig. 2 is a side elevation thereof. Fig. 3 is an end view of the device. Fig. 4 is a vertical longitudinal section. Fig. 5 is a longitudinal section taken on a horizontal plane. Fig. 6 is a plan view of the device.

Referring to the drawing by reference characters wherein like parts are indicated by like characters throughout the several views:—My device comprises two rail sections 1 and 2 having enlargements on their adjacent ends, the enlargement on the section 2 comprising on the inner side of the rail a vertical wall 3 which is made integral with the web, the base and the tread of the rail and extends upwardly from the said base to a point slightly below the plane of the lower face of the tread and it is then cut off and inclined upwardly to the edge of said tread. On the other side of the rail is integrally formed a wall 4 which is of a formation similar to that of the wall 3 with the exception that it extends up to the plane of the upper face of the tread and forms a part of said upper face. The enlargement

5 on the other rail section 1 is in cross section similar to that on the rail 2, but the length of the said enlargement is considerably greater than the length of the enlargement on the end of the section 2 for the purpose as hereinafter to be described. Formed in the enlargement 5 is a socket 6 which is of dove-tailed formation in horizontal section and extends upwardly in the said enlargement from the lower face thereof. The upper face of this socket is parallel with the lower face of the base member of the rail and lies in a horizontal plane. On the end face of the rail section 2 and integral with the enlargement on the end thereof is an outwardly projecting dove-tailed tongue 7 which is of such shape as to fit within the socket in the enlargement on the rail 1, but is of such dimensions as to allow the said tongue to have a slight amount of longitudinal movement within the said socket so that when the rails are held together by the engagement of this tongue and the socket the rails may be allowed to expand or contract by virtue of the loose connection between the tongue and the socket. Projecting outwardly from the base portion of the section 2 is a flange 8 which is integral with the tongue 7 and fits within the cut-away portion 9 in the lower face of the enlargement 5 on the end of the section 1. These rails after having been joined in the manner described are placed on a base plate 10 which has a flat supporting portion 11 on which the bases of the rails rest and on one side of the said plate and extending throughout its length is an upwardly extending flange 12. This flange portion engages one edge of the base of the rail. On the other side of the base plate 10 is formed at each end thereof an upwardly and inclined projecting hook-shaped members 12' which members overhang the bases of the rails and lie in contact with both the base and the web clamping the rail in place upon the supporting plate 11.

A slot 13 is formed in the base 10 adjacent the flange 12 and extends parallel thereto. Slidably mounted in this slot 13 and dove-tailed therein is a plate 13' having a hook 13'' on one end thereof which overhangs and engages the base of the rail. This plate 13' is provided with a plurality of holes 14'' to accommodate spikes to maintain the device in place on a tie. These hook-shaped members 12' are spaced apart

a distance slightly greater than the combined length of the enlargements on the ends of the rail sections so that when the rail sections are separated in expanding there will be allowed between the hook-shaped members sufficient space to allow such expansion. It is to be understood that these enlargements on the outer side of the rail project between the hook-shaped members and co-act with the hook-shaped members to prevent longitudinal movement of the rail.

Between the hook-shaped members on the edge of the supporting plate 11 is an upwardly extending flange 14 which contacts with the lower edge of the enlargements and has notches 14' therein in which are adapted to be engaged spikes for holding this side of the base plate to the tie.

It is to be noted that I have provided a device which will successfully hold the ends of two rail sections together, yet which will allow the said sections to expand under the action of heat.

I have further provided means which will prevent the movement of the rail sections bodily in either a longitudinal or a vertical direction, and I have still further provided means which will prevent the movement of the said rail sections in a transverse direction. I do not wish to be limited to the particular embodiment of my invention shown, for it is obvious that numerous changes may be made within the scope of the claims without departing from the spirit of the invention.

What is claimed is:—

1. In a device of the class described, two rail sections, enlargements on the end of each section, a dove-tailed socket formed in one enlargement, a dove-tailed tongue on the other enlargement and extending into

the said socket, a plate projecting from one of said enlargements and integral with said tongue adapted to fit in a cut-away portion in the other enlargement, a base plate comprising a supporting plate, an upwardly extending flange on one edge of said supporting plate, hook-shaped members on the other edge of said supporting plate and at the ends thereof, said members projecting over the base of the rails and clamping the same between them and the supporting plate, the distance between the inner faces of said hook-shaped members being slightly greater than the combined length of the enlargements on the rail sections, and a flange formed on the edge of said supporting plate between said hook-shaped members.

2. In a device of the class described, a rail having a socket on one end thereof, a second rail having a tongue on the end thereof constructed and arranged to interlock in said socket, a plate for supporting the base of the rail consisting of a base, upwardly extending hook-shaped members constructed and arranged to engage the ends of the rails on one side of the web thereof, the said base plate having a groove formed in the opposite side thereof, a plate slidably mounted in said groove and a hook-shaped member formed integral with said plate and constructed to engage one of the rails upon the opposite side of the web.

In testimony whereof, I affix my signature, in the presence of two witnesses.

CHARLIE M. COX.
